UNITED STATES PATENT OFFICE.

THOMAS W. B. WATLING, OF CHICAGO, ILLINOIS.

DESIGN FOR A WEIGHING-SCALE FRAME OR CASING.

46,878.

Specification for Design.

Patented Feb. 16, 1915.

Application filed May 9, 1914. Serial No. 837,588. Term of patent 14 years.

To all whom it may concern:

Be it known that I, THOMAS W. B. WATLING, a citizen of the United States, and a resident of Chicago, in the county of Cook and State of Illinois, have invented a new original, and ornamental Design for a Weighing-Scale Frame or Casing, of which the following is a specification, reference being had to the accompanying drawing, forming part thereof.

In the drawing, Figure 1 is a front elevation and Fig. 2 is a side elevation of a weighing scale, showing my new design.

I claim:

The ornamental design for a weighing scale frame or casing, as shown.

THOMAS W. B. WATLING.
